(57) **CLAIM**

We claim the ornamental design for a data capture device, as shown and described.

DESCRIPTION

FIG. 1 is a perspective view of a data capture device according to our new design;

FIG. 2 is another perspective view thereof;

FIG. 3 is a top view thereof;

FIG. 4 is a bottom view thereof;

FIG. 5 is a first side view thereof;

FIG. 6 is a second side view thereof;

FIG. 7 is a back view thereof; and,

FIG. 8 is a front view thereof.

The broken lines are directed to environment and are for illustrative purposes only. The broken lines form no part of the claimed design for that particular embodiment.
